UNITED STATES PATENT OFFICE.

W. T. VANN, OF MACOMB, ILLINOIS.

IMPROVED HORSESHOE-NAIL POINTER.

Specification forming part of Letters Patent No. 91,797, dated June 22, 1869.

To all whom it may concern:

Be it known that I, W. T. VANN, of Macomb, in the county of McDonough and State of Illinois, have invented new and useful Improvements in Horseshoe-Nail Pointers; and I do hereby declare that the following is a full and exact description of the same, reference being had to the accompanying drawings, and to the letters of reference marked thereon.

This invention relates to a machine for pointing horseshoe-nails, and consists mainly, in the employment of a lever having a spring hammer or swage, in connection with a proper pointing-block.

The details of construction and manner of operation will be fully described hereinafter.

In the drawings, Figure 1 represents a side elevation of my improved machine; Fig. 2, a plan view, and Fig. 3 a side elevation of the spring-hammer detached.

To enable others skilled in the art to make and use my invention, I will now proceed to describe fully its construction and operation.

A represents a solid piece of suitable metal, which may be termed the "anvil" or "pointing" block. This is provided upon its lower side with the projection *a*, by means of which it may be clamped in a vise, or otherwise suitably secured to a firm foundation.

B represents a lever, of suitable construction, provided with a slot, *b*, as shown. This lever is connected to the pointing-block by means of a hinged arm, *c*, which, extending up through the slot *b*, is securely fastened by the nut *b'*, as is clearly shown in the drawings. The lever *B* is also provided with an additional slot, *d*, over the ends of which hang the catches *d'* *d''*.

E represents a hammer or swage, the face *e* of which corresponds in size with and rests in the slot *d*. This hammer is provided with a head, *e'*, the edges of which overhang the sides of the lever, so that the hammer cannot pass

through the slot. It is inserted in place by removing the catch *d'*. Beneath the edges of the hammer-head are placed suitable springs, the coiled being preferable. The face of the hammer-head is suitably recessed, for the purpose of forming the head of the nail, and so, also, the face of the pointing-block is recessed and given a proper bevel to assist in shaping the nail.

The operation is as follows: The blocks *A* having been suitably secured in any proper manner, the machine is ready for operation. The nail should then be placed upon the lower swage, with its point in the recess. The lever, which is thrown up out of the way when not in use by means of the weight attached to its rear end, is then brought down upon the nail. The swage *E* should then be struck a smart blow with a hammer. The operation is then completed.

The slot *b* permits the lever to be adjusted for larger or shorter nails, as may be desired.

By the machine described I am enabled to point my nails uniformly, so that each one, when driven, emerges from the hoof upon the same line. I can also point them much more rapidly than they can be made by hand.

Having thus fully described my invention, what I claim as new, and desire to secure by Letters Patent, is—

The machine described, consisting, essentially, of the swage *A*, with projection *a*, swage *E*, with face *e* and head *e'*, and the adjustable lever *B*, the whole being constructed and operated in the manner described, for the purpose set forth.

This specification signed and witnessed this 16th day of February, 1869.

W. T. VANN.
